United States Patent Office

Des. 204,390
Patented Apr. 12, 1966

204,390

TABLE

Raymond O. Bodicky, 3834a Fillmore,
St. Louis, Mo. 63116

Filed Jan. 25, 1965, Ser. No. 83,549

Term of patent 14 years

(Cl. D33—14)

FIG. 1

FIG. 2

FIG. 3

FIG. 4

FIG. 5

FIG. 6

FIG. 1 is a plan view of a table embodying my design, wherein the top is octagonal;

FIG. 2 is a side elevation of FIG. 1;

FIG. 3 is a section taken on line 3—3 of FIG. 1;

FIG. 4 is an isometric view of the embodiment shown in FIG. 1;

FIG. 5 is a plan view of a modified table embodying my design, wherein the top is circular; and

FIG. 6 is a side elevation of FIG. 5.

The dominant features of my design reside in those portions shown in full lines on the drawings.

I claim:

The ornamental design for a table, as shown and described.
